EDWARD J. BRANDT, OF WATERTOWN, WISCONSIN, ASSIGNOR TO BRANDT AUTOMATIC CASHIER CO., OF WATERTOWN, WISCONSIN, A CORPORATION OF WISCONSIN.

COIN-HANDLING MACHINE.

Application filed December 10, 1919. Serial No. 343,710.

The present invention is a machine for handling coin, and more particularly for making change in transactions where the expeditious delivery of the exact amount of change is a desideratum.

The object of the present invention primarily is to provide a machine for making change the parts of which are so related as to attain an exceeding simple organization of the machine structure; a highly compact arrangement of the operative elements, and a resultant relative low cost of manufacture in the production of the parts, as well as their assembly in the completed machine. The machine, therefore, requires but small space for its accommodation, and the simplicity of its construction insures a minimum degree of liability to impairment or derangement of its parts.

The invention also has in contemplation the production of a coin handling machine in which the change-making instrumentalities are controlled by a plurality of keys placed in banked relation to afford the most convenient access by the operator, and so arranged in respect to each other that the formation of the various change combinations within the range of the machine may be effected with rapidity and ease.

Furthermore, the invention also aims to provide a machine of the character mentioned in which but a minimum expenditure of power is required for the operation of the change-making instrumentalities, and wherein the power is directly applied to the several coins to be displaced in making up the various change combinations. This demands but little effort by the operator in manipulating the actuating devices and enables free operation of the machine.

A further object to be attained is the construction of the change-making devices in such manner that the power required for their operation is uniformly distributed therethrough to the ultimate point of application to the coin to be ejected.

Furthermore, the present invention also seeks to provide simple and efficient mechanism for locking the coin ejectors against movement under predetermined conditions prevailing in the coin receptacles, thereby preventing operation of the machine when the supply of coins of one or more of the

denominations necessary for completing any particular change combination has become depleted.

Other objects and advantages of the invention will appear as its character more fully is developed in the subjoined description, the invention consisting substantially in the novel construction, combination and arrangement of parts hereinafter specified, illustrated in the accompanying drawings, and finally pointed out in the appended claims.

One adaptation of the invention forms the basis of the present disclosure, but this is to be understood only as an illustrative embodiment thereof and is, therefore, not to be taken in a restrictive or limiting sense.

In the drawings—

Fig. 1 is a front elevation, partly in section, of a coin handling machine embodying the principles of the present invention.

Fig. 2 is a vertical sectional view of the machine across its narrow dimension.

Fig. 3 is a top plan view thereof, partly in section.

Figs. 4, 5 and 6 are detailed sectional plan views, on an enlarged scale, through one of the coin receptacles, illustrating the coin ejector thereof and its locking bolt in different positions.

Referring now in detail to the accompanying drawings, the numeral 10 designates the casing of the herein described machine. This is substantially rectangular in its cross sectional plan contour, but it is obvious that its form in this respect may be varied. The rear wall of the casing 10 rises to a point elevated above the front wall thereof, as clearly illustrated in Fig. 2, where a top 11 is provided and against which a coin tray 12 is designed to rest. The casing 10 is equipped with a bottom plate 13, which latter is set into the lower end of said casing at a point above the lower edges of its walls, thereby providing a clearance space beneath said plate. At the front of the casing 10 a horizontal guide plate 14 is located, which plate extends between the side walls of the casing, and in said plate 14 is positioned the series of operating keys, arranged in bank formation, to be hereinafter described. It will thus be seen that the front of the casing, at the point where the operating keys are located, is in a much lower plane

70

105

than the rear of the casing, and said guide plate 14 is likewise at a point below the lower end of the coin tray 12.

Extending across the casing 10, and disposed beneath the lower end of the coin tray 12, is a coin delivery chute 15, said chute being substantially U-shaped in cross section, and inclining from one side of the casing 10 to the opposite side thereof, where it terminates in a delivery receptacle 16. By arranging the delivery chute 15 as indicated, the same is immediately below the coin tray 12, and as the coins are discharged from the latter they fall into said chute and pass down the same to the delivery receptacle 16. This arrangement also enables the delivery chute 15 to be placed substantially at the mid-portion of the casing 10 between the front and rear walls thereof, the same being positioned between the operating keys and the coin tray, and likewise affording space between the coin tray 12 and the rear wall of the casing 10 for accommodating certain of the operating elements to be hereinafter described. The walls of the delivery chute 15 are parallel and pass straight through the machine from one side to the other. The chute, therefore, can be placed so that it will discharge either to the right or left side of the machine.

The casing constructed as above described affords a highly compact structure, and permits the mechanism of the machine to be arranged in small compass, thereby economizing in the size of the casing and requiring but comparatively little space for its accommodation when in use.

The coin tray 12 includes a plurality of coin receptacles or chutes 17 formed by the back of the tray 12 and a plurality of side walls 18. The lower ends of the side walls 18 of each chute are of wider dimension than the upper ends thereof, and are slightly curved towards each other, as at 19, to prevent frontal displacement of the coins except in the manner hereinafter noted. The lower extremities of the bent portions 19 are cut away to form discharge notches 20, and said notches are immediately contiguous to the bottom 21 of the tray 12, and thereby provide egress points at the lower ends of the chutes 17 for the coins when being displaced therefrom. The discharge notches 20 may vary in size in accordance with the thickness of a given denomination of coin or in accordance with the number of coins of a given denomination to be displaced from the respective chutes when the ejecting mechanism is actuated. For instance, it may be desirable to discharge two or more pennies from the chute containing the same, or other denominations of the coins may be discharged in this manner at a single movement of the ejecting mechanism, dependent upon the particular change combination

which it is desired to make. In such event the varying sizes of the discharge notches 20 will provide for the proper displacement of the coins.

The bottom 21 of the tray 12 has a series of transverse grooves 22, one of which is arranged beneath each of the coin chutes 17, and each of these grooves 22 receives a coin ejecting finger 23 which is pivotally connected, as at 24, to the upwardly extending short arm of a bell crank lever 25. These bell crank levers 25 are each provided with oppositely disposed trunnions 26 fitted in a groove 27 extending longitudinally of a bearing ledge 28 carried by the rear wall of the casing 10, and arranged at an elevated point above the bottom 13 of the casing. Each of the bell crank levers 25 carries a lug 29, which is arranged at the front edge of the short arm of said lever, and pivotally connected to each of said lugs 29 is a guide pin 30 that engages the ejecting finger 23 of the particular lever 25 with which the guide pin 30 is associated. A coil spring 31, of relatively weak strength, surrounds each of the guide pins 30, and exerts its pressure against the ejecting finger 23 immediately above to press the ejecting finger upwardly, and maintain it in proper operative relation to the groove 21 of the particular coin chute 17 with which the guide finger co-operates to insure its contact with the lowermost coin of the stack in that chute.

At one side wall 18 of each of the chutes 17 is arranged a leaf spring 32 having its upper end rigidly connected to said wall, as by riveting or other suitable fastening, while its lower end is free to move with relation to said wall. These springs are relatively narrow at their upper ends and comparatively broad at their lower ends. The purpose of narrowing the upper ends of the springs is to provide a full clearance between the upper portions of the side walls of each chute so that the coins in bulk can be inserted easily and not contact with the springs during such insertion. In doing this the coins are held between the thumb and a finger somewhat above the bottom of the coin tray and are filled into the machine with a downward motion. The wedge shape of the springs insures the easy entrance of the coins in bulk into the respective chutes 17 with a gradual wedging action, the coins clearing the rigid portions of the springs at their narrow upper ends and contacting only with the lower broadened ends which gradually and gently are forced back as the coins enter their respective chutes. The width of the lower portions of the springs 32 is such as to contact with the adjacent edges of the coins, whereby extent of movement of the lower ends of the springs away from the side walls 18 is limited by the coins. This condition is utilized as will presently appear.

It has been stated that the present invention seeks to provide simple and efficient mechanism for locking the coin ejectors against movement under predetermined conditions prevailing in the coin receptacles and thereby preventing operation of the machine when the supply of coins of one or more denominations has become depleted. Preferably this locking of the coin ejectors is effected when a predetermined number of coins remains in the chute, thus making it possible for a limited number of payments still to be made upon freeing the machine of its locked condition as hereinafter described. It is obvious, however, that the supply of coin may be wholly depleted before the locking action ensues, in which event no further payments can be made until the chute from which the coins have been completely discharged has been refilled with the coins of the denominations which it contains. Inasmuch as the locking of the machine with a predetermined number of coins still remaining in the chutes gives notice to the operator of the necessity of replenishing the supply of coin, but still permits limited payments to the extent of the number of coins remaining, the machine is illustrated as adapted to meet these latter conditions.

To this end the lower forward edge of each of the springs 32 is cut away to form a clearing notch 33. The dimensions of this notch are such as to receive the combined thickness of the predetermined number of coins which it is intended shall remain in the chute after the coin ejectors have become initially locked. This number may be one, two, three or more as desired. So long as the stack of coins in the chute exceed in number the coins which the notch 33 will receive, the movement of the lower end of each spring 32 away from the side wall 18 is limited by contact with the excess coins. When, however, the stack becomes reduced to the predetermined number under which the locking action arises, the notch 33 permits the lower end of the spring 32 to clear the remaining coins and the machine becomes locked. By the formation of the notch 33 a finger 34 is provided at the lower extremity of each spring, and each of said fingers 34 carries at its rear edge an engaging tooth 35 the free end of which is received by a notch 36 (Fig. 4) extending crosswise of a locking bolt 37, one of which is provided for each of the coin chutes 17. These locking bolts 37 are slidably mounted in a groove 38 formed at the rear edge of the bottom 21 of the coin tray 12, said groove 38 intersecting the grooves 22. The inner end of each of said bolts 37 is beveled, as at 39, so as to present an inclined contact face to the inner end of the adjacent ejecting finger 23. Each locking bolt 37 is designed to be projected across the mouth of the adjacent groove 22 which guides the ejecting finger 23 to the lower end of the particular coin chute with which the bolt is associated. In this manner, when the bolt is projected entirely across said groove, 70 the forward movement of the ejecting finger 23 is barred, and this, therefore, locks the machine against discharge of coins from the chute until the locking bolt 37 thereof has been retracted. The projection of the 75 locking bolts 37 across the grooves 22 is effected by the several springs 32, but not until the stack of the coins in the respective chutes has been reduced in number to such an extent, as above indicated, that the notches 80 33 will permit the springs to clear those coins remaining in the chutes beneath said notches. When this condition arises the lower ends of the springs 32 move inwardly, and at such movement the teeth 35 propel their respective locking bolts 37 across the grooves 22. The relation of the parts just described under the conditions recited is illustrated in Fig. 6. This is the locked condition of the machine. In Fig. 5 the relation of the parts is illustrated as when the machine is in operating condition for the making of payments. At this time the supply of coin in each of the chutes is such that the edges of the coins above the notch 95 33 of the spring 32 are in contact with the broadened lower portions of said spring. This contact of the coins forces the spring 32 of each chute towards the side wall on which it is supported and holds the spring in that position, and the beveled end 39 of the bolt 37 extends into the path of forward movement of the ejecting finger 23. In this movement of said finger its forward end slides over the beveled end of the bolt 37, thereby forcing the bolt backwardly in the groove 38, and moving the lower end of the spring 32 away from contact with the edges of the coins and towards the side wall 18. The coins of the stack, therefore, may drop 100 105 freely by gravity to the lower end of the chute. Fig. 4 illustrates the relation of the ejecting finger and the locking bolt, together with the retracted position of the lower end of the spring 22 and its clearance relation 110 to the edges of the coin, as just described. After discharge of the lowermost coin the ejecting finger 23 moves rearwardly, and after it passes the beveled end of the bolt 37 the spring 32 asserts itself to restore the locking bolt to the position illustrated in Fig. 5, at which time further movement of the bolt across the groove 22 is prevented by the lower broadened end of the spring 32 again contacting with the edges of the 115 120 125 130 coins above the notch 33.

Assuming the stack of coins to become depleted to the extent that only the predetermined number remain below the notch 33, the clearance afforded by that notch per-

mits the lower end of the spring to move to the added extent of projecting the bolt 37 entirely across the groove 22, and thereby establishing locked condition of the machine. 5 The fact, however, that a predetermined number of coins still remains in the chute enables further payments to be made limited to the extent of the number of these coins. This is desirable where it is not possible for 10 the operator immediately to insert a stack of the coin in the chute when the machine has become locked. To permit the machine to be cleared of this locked condition a releasing slide 40 is mounted in suitable bearings 41 carried by the tray 12, said slide extending across the entire width of the tray and having a plurality of contact pins 42 which project through slots 43 in the tray. 15 One of said contacting pins 42 extends into each of said chutes 17 and into position for engagement with the spring 32 thereof. By pushing the slide 40 so that the pins 42 contact with the springs 32, the latter move towards the side walls of the chute on which 20 they are mounted, and the bolts 37 move away from the grooves 22 to clear these grooves for forward movement of the ejecting fingers 23. The slide 40 may be held in this releasing position, a notch 44 being 25 formed therein for receiving a locking pawl 45, and while so held it is obvious that the coins remaining in the chutes may be discharged therefrom.

30 If it be desired that the locked condition of the machine shall not arise until all the coins have been discharged from the several chutes 17, the notches 33 will be dispensed with, the lower ends of the springs 32 remaining of uniform width, and affording 35 no provision for clearance of any of the coins until the entire stack has been discharged.

40 The horizontal arms of the bell crank levers 25 project towards the front of the machine, and to a point beyond the discharge chute 15. At their forward ends they are engaged by a plurality of actuating plates 46. These plates are formed of thin attenuated metal, and each is provided with a 45 vertical key stem 47 terminating at its upper end in a contact button 48. The plates 46 are disposed between the guide plate 14, through which said key stems 47 project, and the upper sides of the horizontal arms of said levers 25, thereby economizing in the space at the forward end of the machine, and at the same time enabling operation 50 of the coin ejecting instrumentalities by a limited movement of the actuating plates. Each of said plates 46 has a downwardly extending guide stem 49 which passes through a suitably formed perforation in the bottom plate 13, and at an appropriate 55 point the stem 49 has formed thereon a pair of shoulders 50 against which the upper

end of a coil spring 51 bears. The lower end of this spring contacts with the bottom plate 13, and said spring 51 serves to return its actuating plate 46 to its normal or uppermost position when pressure is released from the key stem thereof. It is to be observed 70 that the key stem 47 and the guide stem 49 of each of the plates 46 are arranged in substantial alignment, so that the pressure applied to the key stem extends directly to the guide stem 49, thereby insuring positive action of the plates 46 when the same are depressed, and giving the most direct application of the power to the plates with a minimum of friction. With the key stem arranged above and the guide stem arranged below each actuating plate 46 a long sliding leverage is obtained which makes possible easy and more uniform operation of the machine, and this is especially true when the 80 longer plates are employed. Furthermore, the location of the guide stems 49 at the under edges of the plates 46 affords a convenient position for the return springs 51 in the economical and compact arrangement of 85 the operative parts within the casing. 90

95 Each of the plates 46 also extends over the requisite levers 25 for operation thereof in the making of the particular change combination for which that particular plate is intended. That only those levers 25 to be included in such operation may be actuated, each of the plates 46 has a notch or notches 52 formed in its lower edge and immediately above the individual lever 25, or levers, not to be actuated on the depression of that plate. As illustrated in Fig. 1, the particular plate 46 shown in elevation therein actuates those levers 25 which will produce ninety cents in change, there being but one notch 52 in this plate, and as the latter is depressed the same contacts with those levers 25 which will cause operation of the ejecting fingers 23 in the fifty-cent, twenty-five-cent, ten-cent and five-cent chutes. 100 105 110

115 As illustrated in Fig. 3, the keys include two banks of twelve keys each, the keys of each bank being disposed in staggered or offset relation with respect to the keys of the other bank. The keys of the first bank are arranged preferably so that the first key at the left hand side of the machine will produce one dollar in change; the next five keys are designed to deliver change in the combinations of ten, twenty, thirty, forty and fifty cents; the next two keys will actuate the delivery instrumentalities for ejecting pennies singly and two at a time, respectively, while the remaining four keys of the first bank are designed for actuating those plates which will produce sixty, seventy, eighty and ninety-cent combinations. In the rear bank of the keys, commencing at the left hand end thereof, the first six keys are designed to actuate those 120 125 130 135 140

plates which will deliver change in combinations of five, fifteen, twenty-five, thirty-five, forty-five and fifty-five cents; the next two are for delivery of three and four-cent combinations, respectively, while the remaining four of the rear bank will actuate those plates by which delivery of the sixty-five, seventy-five, eighty-five and ninety-five cent combinations are effected. This arrangement 10 positions the key for the one dollar combination at the most convenient point, and where it is freely accessible, while those keys for delivering single pennies, and in combinations of two, three and four, are arranged 15 at substantially the centers of the two banks.

By reference to Figs. 1 and 2 it will be noted that the front bank of the keys does not extend as high as the rear bank. This 20 makes it possible to operate any key of the rear bank without curving the finger and without the necessity of avoiding contact with the front bank. The degree of depression of the keys of the rear bank carries the same, when operated, only as low as the 25 plane occupied by the keys of the front bank in their normal position, or when they are at rest. The keys, therefore, of the rear bank can be operated with facility and ease regardless of the presence of the front bank.

30 The spring 51 of each actuating plate 46, acting directly upon the latter, will restore the plate to its normal position when pressure on the key stem is removed, but this does not restore the bell crank levers 25 to 35 their normal positions. To effect this a retracting spring 53 connects each of said levers with the ledge 28, so that when the plates 46 are raised by their respective springs 51, the levers 25 which have been 40 depressed thereby are also restored to their normal positions by the springs 53 connected thereto.

In the operation of the herein described machine, the several chutes 17 being supplied 45 with the required coins of the several denominations designed to be placed therein, depression of the particular actuating plate 46 by the key stem 47 thereof actuates the levers 25 in the particular change combination controlled by that particular plate, thereby projecting the ejecting fingers 23 forwardly in the grooves 22 of the several chutes of the coins included in that combination. The lowermost coin of 50 each of these several stacks is thereby ejected into the delivery chute 15 where the same gravitates to the delivery receptacle 16. Pressure being released from the key stem 47 of the plate, the spring 51 thereof raises the plate to its normal position, and the springs 53 of the levers 25 thereby 55 actuated likewise restore these levers to their normal position and retract the ejecting fingers 23 from beneath the stacks of the 60 coins. So long as a sufficient number of coins

in excess of those received by the notches 33 of the springs 32 remain in each stack, the spring 32 of the chute of that stack is prevented projecting the locking bolt 37 across the groove 22 of that chute, and the bolt is 70 permitted to advance only to the position illustrated in Fig. 5 where its beveled end 39 may be contacted by the forward end of the ejecting finger 23 in the advancing movement of the latter. The broadened lower 75 end of the spring, therefore, holds the bolt 37 in its operative working position. As the ejecting finger forces the bolt backwardly in the groove, as illustrated in Fig. 4, the lower end of the spring 32 is released 80 from its contact with the coins so that the coins may freely gravitate to the lower end of the chute 17 to take the place of the lowermost coin ejected by said finger. When the stack of coins has been reduced to the point 85 that only the predetermined number whose combined thickness will be received by the notch 33 remains, clearance is afforded for the movement of the lower end of spring 32 and the same moves the locking bolt 37 entirely across the groove 22, thus precluding 90 advancing movement of the ejecting finger 23. The machine thereby becomes locked, and until the chute has been replenished 95 with a new supply of coin, or until the releasing slide 40 has been operated to clear the machine of its locked condition, the ejecting finger of the particular chute which has become depleted of its coin is no longer 100 operative.

The machine described provides a compact organization of the parts and the application of the power from the key stems 47 to the coin in the chutes is direct and distributed in such manner as to afford positive and easy operation of the several elements included in the change-making instrumentalities.

I claim:

1. In a machine of the class described, a 110 coin receptacle, a coin ejector operatively related thereto, means for locking the ejector against operation, and means within the receptacle for positioning said locking means in locking relation to said ejector, said positioning means being held in non-operating position by the coins in the receptacle until a predetermined condition in the supply of coins has arisen.

2. In a machine of the class described, a 120 coin receptacle, a coin ejector operatively related thereto, means for locking the ejector against operation, and a resilient device within the receptacle for positioning said locking means in locking relation to said ejector, said resilient device being held in restraint by the coins in the receptacle until a predetermined condition in the supply of the coins has arisen.

3. In a machine of the class described, a 130

coin receptacle, a coin ejector operatively related thereto, a locking bolt adapted to be projected across the path of movement of the ejector when the receptacle is emptied of its coins, and means for holding said locking bolt in a clearance position for gravity drop of the coins, in a locking position with a predetermined number of coins remaining in the receptacle, and in an operative position when the receptacle is supplied with coins for normal payment.

4. In a machine of the class described, a coin receptacle, a coin ejector operatively related thereto, a locking bolt adapted to be projected across the path of movement of the ejector when the receptacle is emptied of its coins, and a resilient device arranged in said receptacle and controlled by the coins present therein for holding said bolt in retracted position.

5. In a machine of the class described, a coin receptacle, a coin ejector operatively related thereto, a locking bolt adapted to be projected across the path of movement of the ejector when the receptacle is emptied of its coins, and a spring arranged in said receptacle and controlled by the coins present therein for holding the bolt in retracted position.

30 6. In a machine of the class described, a coin receptacle, a coin ejector operatively related thereto, a locking bolt adapted to be projected across the path of movement of the ejector, and a spring arranged in said receptacle and controlled by the coins present therein for holding the bolt in retracted position, said spring having provision for actuating said bolt to project the same across the path of movement of the ejector when a predetermined condition in the number of coins in the receptacle has arisen.

45 7. In a machine of the class described, a coin receptacle, a coin ejector operatively related thereto, a locking bolt adapted to be projected across the path of movement of the ejector, and a spring arranged in said receptacle and controlled by the coins present therein for holding the bolt in retracted position, said spring having provision for actuating said bolt to project the same across the path of movement of the ejector when a predetermined condition in the number of coins in the receptacle has arisen, and means co-operating with the spring for restoring the latter to retracted position to retract said bolt.

60 8. In a machine of the class described, a coin receptacle mounted for gravity feed of the coins to discharging position, a coin ejector operatively related to said receptacle, means for locking said ejector against operation, and means cooperating with the coins in the receptacle for holding the locking means in non-locking position until a predetermined condition in the supply of the

coins has arisen, the movement of said ejector to coin-discharging position serving to release said holding means from co-operative relation with said coins and permitting the latter freely to gravitate to discharging position.

9. In a machine of the class described, a coin receptacle mounted for gravity feed of the coins to discharging position, a coin ejector operatively related thereto, means for locking said ejector against operation, and a resilient device co-operating with the coins in the receptacle for holding the locking means in non-locking position until a predetermined condition in the supply of the coins in the receptacle has arisen, said resilient device being releasable from co-operative relation with the coins by movement of the ejector to coin-discharging position, whereby to permit the coins freely to gravitate to discharging position.

10. In a machine of the class described, a coin receptacle mounted for gravity feed of the coins to discharging position, a coin ejector operatively related thereto, a bolt adapted to be projected across the path of movement of the ejector for locking the ejector against movement, and means associated with said bolt and co-operating with the coins in the receptacle for holding the bolt in non-locking position until a predetermined condition in the supply of the coins in the receptacle has arisen, said holding means being releasable from co-operating relation with the coins by movement of the ejector to coin-discharging position, whereby to permit the coins freely to gravitate to discharging position.

11. In a machine of the class described, a coin receptacle mounted for gravity feed of the coins to discharging position, a coin ejector operatively related thereto, a bolt adapted to be projected across the path of movement of the ejector for locking the ejector against movement, and a spring arranged in the receptacle and connected to the bolt, said spring co-operating with the coins in the receptacle for holding the bolt in non-locking position until a predetermined condition in the supply of the coins in the receptacle has arisen, said spring being releasable from co-operating relation with the coins on movement of the ejector to coin-discharging position, whereby to permit the coins freely to gravitate to discharging position.

12. In a machine of the class described, a coin receptacle mounted for gravity feed of the coins to discharging position, a coin ejector operatively related thereto, a bolt adapted to be projected across the path of movement of the ejector, the inner end of said bolt being beveled for engagement by the coin ejector, and actuating means associated with said bolt for positioning the same

in locking relation to said ejector when a predetermined condition in the supply of coins in the receptacle has arisen, said actuating means being held in restraint by the 5 coins in the receptacle but releasable from engagement with the coins on movement of the coin ejector to coin-discharging position, whereby to permit the coins freely to gravitate to discharging position.

10 13. In a machine of the class described, a coin receptacle mounted for gravity feed of the coins to discharging position a coin ejector operatively related thereto, means for locking said ejector against operation, and 15 means complete within said receptacle co-operating with the coins therein for holding the locking means in non-locking position until a predetermined condition in the supply of the coins in the receptacle has arisen, 20 the movement of said ejector to coin-discharging position serving to release said holding means from co-operative relation with said coins and permitting the latter freely to gravitate to discharging position.

25 14. In a machine of the class described, a coin receptacle mounted for gravity feed of the coins to discharging position, a coin ejector operatively related thereto, means for locking said ejector against operation, and a 30 yielding downwardly-widening leaf-spring guide fastened near its top in said receptacle, said leaf-spring guide controlling a locking position, an unobstructed gravity-feed position and an operating position of the locking 35 means.

15. In a machine of the class described, a coin receptacle mounted for gravity feed of the coins to discharging position, a coin ejector operatively related thereto, means for 40 locking said ejector against operation, and means within the receptacle for controlling a locking position, an unobstructed gravity-feed position, and an operating position of the locking means.

45 16. In a machine of the class described, a coin receptacle mounted for gravity feed of the coins to discharging position, a coin ejector operatively related thereto, and means for locking said ejector against operation, 50 said locking means having capacity to be positioned relatively to said ejector for totally locking the latter against coin-discharging movement, for an unobstructed gravity-feed of the coins to discharging position, and for operation relatively to the coins to effect their discharge from the receptacle. 55

17. In a machine of the class described, a coin receptacle mounted for gravity feed of the coins to discharging position, a coin ejector operatively related thereto, means for locking said ejector against operation, said locking means having capacity to be positioned relatively to said ejector for totally locking the latter against coin-discharging 60 movement, for an unobstructed gravity-feed of the coins to discharging position, and for operation relatively to the coins to effect their discharge from the receptacle, and means within the receptacle influenced by 65 predetermined conditions in the supply of the coins therein for determining the positioning capacity of the locking means in the operation of the machine.

18. In a machine of the class described, a coin receptacle mounted for gravity-feed of the coins to discharging position, a coin ejector operatively related thereto, means for locking the ejector against operation, said locking means having capacity to be positioned relatively to said ejector for totally locking the latter against coin-discharging movement, for an unobstructed gravity feed of the coins to discharging position, and for operation relatively to the coins to effect 70 their discharge from the receptacle, and a pressure device within said receptacle influenced by predetermined conditions in the supply of the coins therein for determining the positioning capacity of the locking 75 means in the operation of the machine.

19. In a machine of the class described, a coin receptacle mounted for gravity feed of the coins to discharging position, a coin ejector operatively related thereto, means for locking said ejector against operation, said locking means having capacity to be positioned relatively to said ejector for totally locking the latter against coin-discharging 80 movement, for an unobstructed gravity-feed of the coins to discharging position, and for operation relatively to the coins to effect 85 their discharge from the receptacle, and a pressure device within said receptacle influenced by predetermined conditions in the supply of the coins therein for determining the positioning capacity of the locking 90 means in the operation of the machine.

100 20. In a machine of the class described, a coin receptacle mounted for gravity feed of the coins to discharging position, a coin ejector operatively related thereto, and means for locking said ejector against operation, and a 105 spring within said receptacle having one of its ends fixed and its other end capable of free movement, the free end of said spring being acted on by the coins in the receptacle and influenced by predetermined conditions in the supply thereof for determining the positioning capacity of the locking means in the operation of the machine.

110 In testimony whereof I have hereunto subscribed my name.

EDWARD J. BRANDT.
